SAFETY RAZOR

Herbert E. Rider, New York, N. Y., assignor, by
mesne assignments, to Frank M. Ashley, New
York, N. Y.

Application April 20, 1938, Serial No. 203,027

3 Claims. (Cl. 30—45)

My invention relates to safety razors.

The object of my invention is to provide an electrically operating safety razor for use with direct current, that may be made at a low cost and is light in weight.

A further object is to provide a construction in which the operating motor is supported in one side of the casing in such a manner as to be operated when the opposite side of the casing is removed for the purpose of inspection and adjustment.

A further object is to provide a razor in which the entire length of the cutting edge of the blade is exposed to view and adapted to contact the skin of a user in the act of shaving.

A further object is to provide a construction in which the blade is mounted and guided to operate in rocking relation to the supporting platen on which it carried, to provide a slicing action by reason of which the beard of a user may be removed without injury to the skin and without any disagreeable sensation by reason of pulling, etc.

Other objects will appear in the following specification in which a detailed description of the construction is set forth.

Referring to the drawing which form a part of the specification:

Fig. 1 is a perspective view of a razor construction embodying my invention and showing the arrangement of the blade edge relative to the guard.

Fig. 2 is a vertical sectional view thru the casing, blade housing and blade, and the exterior view of the motor and means for holding it in the casing.

Fig. 3 is a plan view of a cross section taken on line 3—3 of Fig. 2.

Fig. 4 is a diagram of the electrical connections used in the construction.

Fig. 5 is a view of one form of blade construction which may be used, showing slots for guiding the blade in a linear movement.

Fig. 6 is a view of a blade construction showing slots for guiding the blade, one of which is formed to provide parallel sides which extend parallel to the edge of the blade, and the other of which extends at a sharp angle to the straight edge of the blade.

Fig. 7 is a cross sectional view taken on line 7—7 of Fig. 2, and illustrating the arrangement of the blade in the housing.

My construction embodies an electro magnet and an oscillatory armature hinged between its ends and mounted in such a manner that its

two ends will be positioned respectively opposite the two ends of the magnet, the armature being made of iron and magnetized to provide a permanent magnet.

It will be noted there are no springs used in the construction of the motor or parts within the casing.

10 indicates a casing made in two parts that are substantially alike in form and size and may be made in the same mold.

The casing is made of insulating plastic material and is formed to provide a recess of rectangular form, indicated by 11, in each part, which are located opposite to each other and serve to hold a metal band 12 rigidly between them.

The band 12 is made from a strip of metal bent into the form illustrated in Fig. 3, and supports an electro magnet 13 and an insulating sleeve 14, as shown in Fig. 2, together with an armature 15 which is pivoted at 16.

The core of laminated metal 17 extends beyond the coil of the magnet and a screw 17'—17' respectively, extends thru the magnet poles and are adjusted relative to the poles of the permanent magnet 15 to control the amplitude of the movement of said magnet and cause it to oscillate.

Extending from the upper end of the permanent magnet 15 is a bar of non magnetic metal 30 such as aluminum, or other suitable material 18, which serves to transmit its movement to the razor blade to reciprocate the same.

The casing is held together in easily separable relation by a nut and screw combination 35 at its lower end, indicated by 19, and at its upper end it is held by a tube 20 which slips over the tubular formed portion 21 of the casing in close frictional relation, said casing being separable on the vertical line 22.

The upper end of the tube 20 is secured to the lower plate 22' of the housing which may be bodily removed from the casing 10, as will be readily understood.

It may be well to note at this time that by removing the razor-blade housing, and removing the nut from the bottom end of the casing 10 the operative magnets may be removed from the casing for inspection or adjustment, and that the adjustments and tests of said parts 50 may be made prior to assembling the parts ready for sale.

Mounted on the plate portion 22' of the housing are mounted two upwardly extending pins 23—23, respectively, secured to the plate in fixed

relation, and small cylinders 24-24 respectively are fitted to said pins to serve as friction rollers which may be easily replaced by new ones in case of excessive wear.

5 The blades 25 and 25' illustrate the same construction except for the form of the end slots 27 and 27', which fit over the rollers or cylinders 24-24.

10 The cutting edge of the blade is indicated by 26 and each blade is provided with a stiff back strip 28 provided with a notch 29 in each end, and a notch 30 midway therebetween to reduce the weight of the blade.

15 The blade is also provided with a rectangular slot 31 into which the upper end of the rod 18 projects and fits in such a manner as to permit the blade shown in Fig. 6 to rise and fall slightly in the slot 27' in action, said blade being pivoted in the slot 27 and therefore the blade 20 will move laterally and upwardly with a swinging motion when driven by the motor, the degree of said motion being governed by the adjustment screws 17'.

25 It will be noted that the adjustment screws 17' are located adjacent the inner wall for the reason that if for any reason the device fails to operate, it will not be injured by an inexperienced person trying to adjust it but must be returned to the makers or an experienced person for such adjustment.

30 The electric current is controlled by a switch 32 of usual construction and is the only part carried by the casing portion opposite to the portion carrying the motor, and this arrangement permits the motor to be inspected and operated in the half of the casing carrying it when the part carrying the switch is removed, the electrical conductors being sufficiently long

to permit operation of the switch and motor when so separated.

35 The cover portion 33 of the housing is pivoted to the plate 22' and serves to guide the blade in its movement, and by swinging the 5 cover upwardly on its pivots 34 the blade may be freely removed from the housing.

10 35 indicates a resistance to reduce the current from 110 volts to a lower voltage suitable for the operation of a motor comprising an elec- 10 tro-magnet of the character described.

15 By pivoting the fixed magnet between its ends as shown the power is increased since each pole of the magnet acts alternately to attract and repel the adjacent ends of the permanent mag- 15 net, as will be readily understood.

Having thus described my invention I claim as new:

1. A safety razor comprising a casing adapted to support a razor blade, said casing comprising a guard on which the blade rests and pins for guiding the blade fixed thereon, and a blade having slots therein for guiding the blade by means of said pins, one of said slots extending at an angle to the other whereby the blade may 25 be caused to swing relative to the guard, and means for reciprocating said blade.

2. The construction defined in claim 1, together with; each of said pins having a cylindrical roller thereon.

3. A safety razor comprising a casing comprising a guard on which a blade may rest, pins carried by said guard portion of the casing, a blade having a slot extending parallel with the edge of the blade adjacent one end thereof and 35 a slot extending at an angle thereto located adjacent the opposite end of the blade, said pins extending thru said slots to guide the blade.

HERBERT E. RIDER.
